MOUNTING

Richard U. Clark, Wilmette, Ill., assignor, by
means assignments, to The Magnavox Com-
pany, Incorporated, a corporation of Indiana.

Application November 10, 1936, Serial No. 110,098

3 Claims. (Cl. 248—27)

The present invention relates to a suspension mounting and more particularly to a device for retaining a condenser, coil, resistor or other electrical component or unit and mounting this unit in a predetermined adjusted position in an opening in a radio or other electrical chassis or frame.

Among the objects of the present invention is to provide a novel suspension mounting and support for such mentioned units having longitudinally spaced resilient gripping members adapted to bite into and resiliently but firmly grip and maintain the unit in axial alignment with the mounting device and in a predetermined adjusted longitudinal position.

A further object of the invention is to provide mechanism for resiliently mounting such a unit or component in the chassis or frame of a radio with the required snugness to hold it firmly in place, but at the same time with sufficient resiliency to withstand severe shocks encountered in handling and shipping the device.

A further object is to provide a novel mounting device so formed and constructed as to be resiliently but firmly retained in the frame or chassis of a radio set, and in turn, resiliently and firmly retain a condenser or other electrical unit or component. By this construction and arrangement, the mounting and/or the electrical unit may be quickly assembled, removed or replaced when the occasion requires.

A still further object of the present invention is to provide a mounting device in which the entire mounting operation may be completed without the use of any tools, jigs, etc., and by unskilled labor. In addition, the condenser or other electrical component may be withdrawn or removed from the mounting by hand and without the use of any tools, as may at present be required during service or for replacement of the electrical component.

Yet another object of the invention is to provide a mounting with oppositely projecting resilient members so formed as to resiliently grip and retain a condenser or other electrical unit or component, and also lock this unit in a firm but pressure release position in the chassis or frame.

Further objects are to provide a construction of maximum simplicity, efficiency, economy and ease of assembly and operation, and such further objects, advantages and capabilities as will later more fully appear and are inherently possessed thereby.

The invention further resides in the construction, combination and arrangement of parts

illustrated in the accompanying drawing, and while I have shown therein a preferred embodiment, it is to be understood that the same is susceptible of modification and change, and comprehends other details, arrangements of parts, features and constructions without departing from the spirit of the invention.

Fig. 1 is a view in perspective of the mounting device as located in a fragment of a radio chassis or other support.

Fig. 2 is a view in vertical cross section through the construction disclosed in Fig. 1.

Figs. 3, 4, and 5 are fragmentary views of alternate forms of the mounting.

Fig. 6 is a fragmentary view in perspective of one form of the novel mounting in which the lower teeth or prongs are of the type shown in Figs. 1, 2, and 4.

Fig. 7 is a similar view but of an alternate form of lower tooth or prong of the type shown in Fig. 3.

Fig. 8 is a fragmentary view in side elevation of another form in which the alternate lower teeth or prongs are formed to receive a support or base of varying thickness.

Figs. 9 and 10 are views in vertical cross section taken in planes represented by the lines 9—9 and 10—10 of Fig. 8.

Referring more particularly to disclosures in Figs. 1 and 2, the novel mounting device preferably consists of an annular flange or base 1 of metal and formed or provided with a central opening and longitudinally spaced resilient grips 2 and 3 projecting in opposite directions. In its preferred form this mounting is made of a stamping with the longitudinally spaced sets of resilient grips 2 and 3 in staggered relation and so formed and arranged that one of them extends upwardly and inwardly and the succeeding one extends in a downward and inward direction to resiliently grip an object at spaced points and thereby provide a more firm mounting or support therefor. These members are constructed of resilient and tempered metal and so shaped and arranged as to resiliently but firmly grip at longitudinally spaced points, the side walls of a unit such as a condenser, coil, resistor or other object, for maintaining in suspension such condenser normally in axial alignment with respect to the mounting device and in a predetermined longitudinally adjusted position without other means of support, and for permitting the condenser to be readily pressure mounted and demounted.

As shown in Figs. 1 and 2, and in the mounting disclosed in Fig. 4, the lower resilient grips

3 are each formed or shaped to provide an annular groove or corrugation 5 for the reception of the plate or pan 6 forming a part of the chassis of a radio set or other structure. By reason of this construction, the mounting device, when pressed into the opening in the plate or pan 6, will lock therewith by a resilient and yieldable grip and be retained against accidental displacement, although allowing for ready pressure removal and/or replacement by manually exerting a push or pull on the mounting device without the use of tools of any kind. Due to this arrangement of locking the mounting and plate by means of the resilient grips, the resilient gripping pressure of these members against the object will be increased or accentuated.

In utilizing my suspension mounting, preferably it is put into use by first pressing the mounting into a suitable opening of a slightly larger diameter, such as the opening in the pan 6 shown in Figs. 1 and 2 and elsewhere, then the condenser 4 is grasped in the hand and moved into the opening in the mounting by a twisting pressure. As the condenser is initially advanced into the opening, one set of the longitudinally spaced resilient but firm gripping members first grips the condenser, or other object which is being mounted, then as the mounted object is further moved into the desired predetermined, longitudinally adjusted position, the other set of longitudinally spaced resilient but firm gripping members likewise grips the surface of the object to be mounted. At this stage a fulcrum action is set up which causes the gripping members in both sets of gripping members to impinge and resiliently but firmly grip the surface of the condenser and automatically axially align it with respect to the mounting device. When the condenser has been moved to the desired position it is there resiliently but firmly held in such longitudinal, predetermined adjusted position without any other supporting means. At the same time it is mounted in such a way as to permit it to yield under abnormal strains or stresses, either axially or longitudinally, such as might be imposed in handling or in use and further permits the ready readjustment of the longitudinal position or the replacement or removal of the condenser. However, if desired my novel suspension mounting may be applied to the condenser or other object to be mounted before it is put in its position for use.

In each of Figs. 1, 2, 4 and 6, the ends or gripping surfaces or points 7 of the spaced members 3, are adapted to bite into the surface or material 55 of the member being held, while the resilient gripping members 2 in Figs. 1 and 2 and the resilient gripping members 8 of the mounting 1^b of Figs. 3 and 7, have ends 9 so formed as to receive and frictionally and tensionally engage the 60 surface or casing of the member 4, so as to retain the member in adjusted position or be seated in grooves or depressions provided therein.

As disclosed in Fig. 4 the upper gripping members 10 of the mounting 1^a may also be formed 65 to provide a relatively sharp edge or end 11 adapted to bite into the material of the member to be held.

In Fig. 5 the upper and lower gripping members 11 of the mounting 12 are similar in contour and 70 the ends 13 thereof are adapted to tensionally grip the member 4 with greater surface area than the forms shown in the preceding views.

In Figs. 8, 9 and 10 there is disclosed an alternate construction of mounting 14 in which the 75 upper resilient gripping members 2 are prefer-

ably of a contour or configuration as shown in Figs. 1 to 5 inclusive, while the lower set 15 and 16 are of similar contour except that the members 15 are formed with a wider groove 17 than the groove 18 shown in Fig. 5 10 and the members 15 are so formed as to frictionally and tensionally engage and be retained in a plate or pan 19 of greater thickness than the plate or pan 20 shown in Fig. 10. Thus by reason of this construction, a standard form 10 of mounting may be employed and locked to the chassis pan, plate or other base even though they may vary in thickness.

The present device is preferably made of some suitable metal which may be readily treated for 15 hardening and spring tempering so that the gripping members may have sufficient resiliency to cause them to resiliently grip the object to be mounted with a resilient but firm grip. In forming the gripping members the conformation of 20 both the bottom and top sets is preferably such that the object to be mounted will be gripped near the free ends of these members.

It will be appreciated that as the object is inserted in the mounting, the contact of the lower 25 set of gripping members with the surface of the object to be retained will tilt or cant the base and the other set of gripping members about the support or base so that the upper set will more forcefully grip or bite into the surface of the object. 30 Also, this base or support will help to retain pressure on the bottom grips and prevent their deformation.

To further prevent the unintentional removal of the condenser by a person, for example, 35 grasping the condenser to move or lift the set in which the condenser is mounted, it may be desirable to so form the lower grips as shown in Figs. 2, 4 and 6 so that the contact edges of the grips bite or cut into the surface of the material 40 of the condenser thus insuring against accidental removal merely by a straight manual upward pull. When it is desired to intentionally remove it, then the condenser is given a pull upwardly with considerable force concomitantly with the twist of the 45 condenser.

To facilitate the application and holding properties of my suspension mounting the ends of the upper resilient grips terminate at an angle to their plane. Thus the leading edge of the grip 50 first impinges and bites into the surface of the object being mounted, and it is desirable when mounting an object therein that it be turned as it is forced into the mounting.

When it is desired that the object or component 55 be either inserted into or withdrawn from the mounting with equal facility, the upper and lower resilient gripping members will preferably be formed as shown in Figs. 3 and 5 so that these members will each present the same surface con- 60 formation and gripping action.

When the mounting is employed for supporting an electrical component, and the pan or base is constructed of metal, it may be advisable to suitably insulate the mounting. This can be readily 65 accomplished by inserting insulating filler or medium between the pan and mounting wherever these two members may contact, and/or between the mounting and object to be retained.

It will be obvious that various modifications of 70 the present device may be made, as for example by forming the end of each gripping member in accordance with the surface contour of the member to be gripped. It may also be advisable to roughen, corrugate or knurl as at 75, the ends of

the gripping members so that they may more readily grip the particular type of material forming the outer surface of the member to be mounted.

From the above disclosure it will be apparent that although the invention is disclosed as mounting a condenser, coil resistor or other electrical unit or component, it is equally well adapted for use in retaining numerous and varied objects which are to be retained in a resilient but firm position, although permitting their ready removal or replacement. It will be further apparent that the conformation of the lower gripping members is such that a curved recess is formed to receive and lock onto an edge of the pan, base to support upon which the object is to be mounted, and thereby anchor the mounting in assembled position.

It is to be understood that although the mounting is disclosed as circular, it may be readily varied in shape to accommodate and retain objects that may be other than cylindrical.

Having thus disclosed the invention, I claim:

1. A suspension mounting device for mounting an object in an opening in a fixed support, comprising in combination a ring-like base member adapted to be seated against said support, opposed longitudinally spaced sets of angularly disposed resilient gripping members extending inwardly from the inner circumference of said base member adapted to resiliently but firmly grip a mounted object at longitudinally spaced regions for maintaining the object in axial alignment with respect to the mounting device, and means adapted to tensionally secure said mounting in the base, the construction and arrangement being

such that one set of gripping members is forced into clamping relation with said object when the base member is assembled in said opening.

2. A suspension mounting device for mounting an object in an opening in a fixed support, comprising in combination a ring-like base member adapted to be seated against said support, opposed longitudinally spaced sets of angularly disposed resilient gripping members extending inwardly from the inner circumference of said base member adapted to resiliently but firmly grip a mounted object at longitudinally spaced regions for maintaining the object in axial alignment with respect to the mounting device and in a predetermined longitudinal position, and means adapted to tensionally secure said mounting in the base, the construction and arrangement being such that one set of gripping members may be clampingly engaged in the opening of the support.

3. In a suspension mounting device adapted to be pressure mounted in an opening of a fixed support to permit pressure mounting and demounting of an object in the device, comprising a body member having a central opening, opposed longitudinal spaced sets of resilient gripping members around said opening extending axially and radially inwardly and adapted to resiliently but firmly grip the mounted object at longitudinally spaced regions for maintaining the mounted object in axial alignment with respect to the mounting device and in a predetermined longitudinal position, said device being adapted to be pressure applied through the opening of a fixed support to engage with said support.
